VACUUM CLEANER

**Tom Conrad Biéth, Alsten, Stockholm, Sweden,
assignor to Electrolux Corporation, Dover, Del.,
a corporation of Delaware**

**Application October 4, 1932, Serial No. 636,132
In Germany December 24, 1931**

8 Claims. (Cl. 230—274)

The present invention relates to vacuum cleaners and more particularly to vacuum cleaners of the type which include a unit mounted horizontally above the floor to which a suction hose 5 is attached.

The object of the invention is to provide a simple structure for directing the air upwardly away from the surface on which the cleaner unit rests.

10 The nature of the invention will become apparent from consideration of the following description taken in conjunction with the accompanying drawing showing a number of embodiments of the invention, and of which:

15 Fig. 1 shows a vacuum cleaner unit embodying the invention;

Fig. 2 shows diagrammatically an arrangement in accordance with the invention;

20 Figs. 3 and 4 are other diagrammatic showings of the invention;

Figs. 5 and 6 are partial sectional views of different embodiments of the invention; and

Fig. 7 is an end view of part of the device shown in Fig. 6.

25 Fig. 1 shows a vacuum cleaner unit of the type disclosed in Engberg et al. Patent No. 1,757,239 dated May 6, 1930. The casing of the cleaner unit is designated generally at 10 and comprises a central cylindrical barrel portion to which are 30 mounted end caps 11 and 12. The cleaner unit is mounted horizontally above the surface 18, for example a carpet to be cleaned, by means of runners 13. The end caps are removably attached to the cylindrical barrel by means of 35 spring clips or other fastening means.

Within the casing 10 is the usual dust bag 9, fan 8 and motor 7. Behind the motor is a filter 16 which may comprise a plurality of pieces of cloth stretched on a framework, and 40 adjacent and behind the filter is a wire mesh 17 for protecting and supporting the filter cloth.

45 The end cap 11 is threaded to receive a hose coupling 15 which has a central opening for flow of air into the casing 10. The end cap 12 is provided with an outlet member generally designated by numeral 24. The outlet member has a part 19 of generally spherical formation in which is the outlet opening 14. The edge of the outlet opening 14 is in a plane oblique to 50 the vertical and offset with respect to the center of the outlet member 24, being in the lower part thereof so that air passing through the outlet opening is directed upwardly away from the floor in order to prevent raising dust. The direction of air flow is indicated by the arrows in

Figs. 2, 3 and 4. The outlet member is internally threaded as shown to receive the coupling member 15 whereby the air hose can be connected to the air outlet.

A series of grid members or bars 25 may be provided across opening 14. Such bars are preferably vertical as shown in Fig. 7 and may have a stream line cross-section to minimize resistance.

Air is drawn by the fan 8 inwardly through 10 cap 11, through dust bag 9, past the motor and out through opening 14, the air being directed upwardly due to the arrangement of opening 14.

If desired, the form of end cap 12 may be made in accordance with Figs. 2, 3 or 4. Fig. 15 2 shows the entire end wall of the cap oblique. Fig. 3 shows a spherical shaped wall 19 formed integral with the remainder of the end cap. Fig. 4 shows an oblique opening formed between two horizontally offset vertical walls 21 and 22. 20

The arrangement of Fig. 5 shows a larger opening 14 obtained by suitably forming the upper part of the outlet member.

In order to obtain the upward inclination of the discharged air, it is not necessary that all 25 the air pass out through the inclined opening. For example, as shown in Fig. 6, there may be an opening 23 in the upper part of the outlet member. Opening 23 may be provided with a surrounding rim having a vertical edge and directing the air flowing therethrough horizontally. 30

The member 24 may be turnably mounted in cap 12 so that the air current may be directed in other directions than upwardly.

The invention may obviously be embodied in 35 other forms than those shown.

What is claimed is:

1. In a vacuum cleaner, the combination with a cylindrical casing having an air inlet opening, means for supporting said casing horizontally above a horizontal surface and means in said casing for producing flow of air, of an air outlet member in the end of said casing having a spherically shaped portion with the convex side thereof facing the outflowing air and having an 45 opening therein, the perimeter of said opening being in a plane oblique to the vertical.

2. In a vacuum cleaner, the combination with a cylindrical casing having an air inlet opening, means for supporting said casing horizontally 50 above a horizontal surface and means in said casing for producing flow of air, of an air outlet member in the end of said casing having a spherically shaped portion with the convex side thereof facing the outflowing air and having an 55

opening therein offset with respect to the center of the member for outflow of air.

3. In a vacuum cleaner, the combination with a cylindrical casing having end caps, one of said caps being formed with an air inlet opening, means for supporting said casing horizontally above a horizontal surface and means in said casing for producing flow of air, of an air outlet member secured to one end of said casing and being disposed substantially wholly within said casing, said member having a spherically shaped portion with the convex side thereof facing the outflowing air and having an opening therein, the perimeter of said opening being in a plane 10 oblique to the vertical.
- 10 caps and having a single opening therein substantially unobstructed with respect to air flow therethrough, the perimeter of said opening being in a plane oblique to the vertical whereby air may pass through said opening in a direction 15 normal to said plane without being subjected within said opening to a change in direction of flow.

4. In a vacuum cleaner, the combination with a casing having an air inlet opening of an outlet member therefor in generally vertical position and having a spherically shaped portion with the convex side thereof facing the outflowing air and having an opening therein, the perimeter of said opening being in a plane oblique to 20 the vertical.

5. In a vacuum cleaner, the combination with a cylindrical casing having an air inlet opening, means for supporting said casing horizontally above a horizontal surface and means in said 30 casing for producing flow of air, of an air outlet member secured to one end of said casing and being disposed substantially wholly within said casing, said member being formed with a single opening substantially unobstructed with respect to air flow therethrough, the perimeter of 35 said opening being in a plane oblique to the vertical so that air passing therethrough is directed upwardly whereby air may pass through said opening in a direction normal to said plane 40 without being subjected within said opening to a change in direction of flow.

6. In a vacuum cleaner, the combination with

a cylindrical casing having an air inlet opening, means for supporting said casing horizontally above a horizontal surface and means in said casing for producing flow of air, of an air outlet member secured to one end of said casing and being disposed substantially wholly within said casing, said member having a spherically shaped portion with the convex side thereof facing the outflowing air and having an opening therein, the perimeter of said opening being in a plane 10 oblique to the vertical.

7. In a vacuum cleaner, the combination with a cylindrical casing having an air inlet opening, means for supporting said casing horizontally above a horizontal surface and means in said 15 casing for producing flow of air, of an air outlet member secured to one end of said casing, said member having an outer threaded aperture disposed in a vertical plane and a portion extending within said casing formed with a single 20 opening substantially unobstructed with respect to air flow therethrough, the perimeter of said opening being in a plane oblique to the vertical whereby air may pass through said opening in a direction normal to said plane without being subjected within said opening to a change in 25 direction of flow.

8. In a vacuum cleaner, the combination with a cylindrical casing having an air inlet opening, means for supporting said casing horizontally above a horizontal surface and means in said 30 casing for producing flow of air, of an air outlet member secured to one end of said casing, said member having an outer threaded aperture 35 disposed in a vertical plane and a spherically shaped portion extending within said casing with the convex side thereof facing the outflowing air and formed with an opening therein, the perimeter of said opening being in a plane oblique to 40 the vertical.

TOM CONRAD BIETH.
